UNITED STATES PATENT OFFICE.

GEORGE E. ADAMS, OF NEW BRITAIN, CONNECTICUT.

DESIGN FOR A BODY PORTION AND BACK-STRAP CONNECTION FOR SUSPENDERS.

SPECIFICATION forming part of Design No. 35,257, dated November 5, 1901.

Application filed May 1, 1901. Serial No. 58,389. Term of patent 14 years.

To all whom it may concern:

Be it known that I, GEORGE E. ADAMS, of New Britain, in the county of Hartford and State of Connecticut, have invented and produced a new and original Design for a Body Portion and Back-Strap Connection for Suspenders, of which the following is a specification, reference being had to the accompanying drawings, forming a part thereof.

Figure 1 of the accompanying drawings is an elevation of a body portion and back-strap connection embodying the present design. Fig. 2 is a section on the line 2 2.

As shown in the drawings, the leading or material features of the present design consist of the downwardly-looped webs A A',

rounded in cross-section, as indicated in Fig. 2, and merging at their upper ends into flat straps or webs B B', the latter in turn merging into the straps C, with the union D for the suspender-end depending from the loops A A'. Eyes D' of the union encircle the loops A A' and are in substantially the same vertical plane above the body of the union.

What I claim is—

The design for a body portion and back-strap connection for suspenders substantially as herein shown and described.

GEORGE E. ADAMS.
